PINWHEEL FEEDING DEVICE

Filed Oct. 31, 1936

FIG. 1.

UNITED STATES PATENT OFFICE

2,113,579

PINWHEEL FEEDING DEVICE

Henry G. Dybvig, Dayton, Ohio, assignor to John
Q. Sherman, Dayton, Ohio

Application October 31, 1936, Serial No. 108,584

24 Claims. (CL 197—133)

This invention relates to a pin wheel feeding device and in more particular to a pin wheel feeding device mounted in an expansible platen.

An object of this invention is to provide an 5 expansible platen having a pin wheel feeding device adapted to feed various widths of record material.

Another object of this invention is to have 10 feeding pins project through variable length slots in the platen.

Another object of this invention is to provide fillers for slots in the platen.

Other objects and advantages reside in the 15 construction of parts, the combination thereof and the mode of operation, as will become more apparent from the following description.

Fig. 1 is a fragmentary perspective view of a typewriter showing my platen.

Fig. 2 is a longitudinal sectional view of my 20 platen taken substantially on the line 2—2 of Fig. 5.

Fig. 3 is an enlarged fragmentary longitudinal sectional view taken substantially on the line 3—3 of Fig. 4 and drawn to a larger scale than 25 the longitudinal sectional view shown in Fig. 2.

Fig. 4 is a fragmentary sectional view taken substantially on the line 4—4 of Fig. 3.

Fig. 5 is a transverse sectional view taken 30 substantially on the line 5—5 of Fig. 2, but drawn to a larger scale than Fig. 2, and a smaller scale than Figs. 3 and 4.

Fig. 6 is an enlarged fragmentary sectional view showing a tooth of the pin wheel feeding device cooperating with the edges of the longitudinal 35 slots as a gear tooth.

The pin wheel feeding device used in this invention incorporates some of the principles disclosed in my copending application Serial No. 88,608 for Pin wheel feed, filed July 2, 1936.

40 In the past it has been general practice to provide round holes in the periphery of the platen of writing machines to permit the feeding pins to project therethrough into engagement with marginally punched feeding holes in superimposed strips of record material. Various attempts have been made to provide pin wheel feeding devices for use with various widths of record material. It has been proposed to use multiple section platens having a plurality of 45 feeding wheels therein, some of which may be moved into inoperative position so as to permit others to be used in advancing the record material. Shields have been provided for covering the holes in the platen that are left vacant by 50 the pin wheels that are in inoperative position.

Other attempts have been made wherein the pin wheel feeding devices are adjustable axially, so as to change the spacing between the pin wheel feeding devices that usually are adapted to engage marginal holes in the superimposed strips of record material. The distance between the pin wheel feeding devices has been spanned by removable platens or platen sections. These may be split so as to permit the easy removal of the sections. In shifting from one width 5 material to another, sections having suitable length are selected for use between the pin wheels.

In the device disclosed herein and forming the invention hereof, a platen having a plurality 15 of equally spaced longitudinal slots in one end has been used. The slots permit the adjustment of one of the pin wheel feeding wheels axially, without interference from the platen. In order to permit the use of the platen between the pin 20 wheels, suitable strips having a tongued and grooved relation with the platen, fill the slots between the pin wheels, so that as the pin wheels are separated the strips are drawn into the slots vacated by the adjustable pin wheel, so as to 25 present a uniform writing surface to the record material advanced in registry past writing position.

In the drawing the reference character 10 indicates the typewriter having a traveling carriage 12 supporting a platen 14. Instead of the carriage 12 traveling to and fro, the type basket could be mounted for reciprocatory movement.

Platen mounting

The platen 14 includes a cylindrical member 16, supported upon a pair of discs or end frames 18 and 20. In order to provide a proper cushion for the impinging type, the face of the cylindrical member 16 is lined with rubber 22. One 40 end of the cylindrical disc 16 is provided with feed holes 24. The opposite end is provided with a plurality of elongated longitudinal slots 26. The pin holes 24 and the slots 26 permit the projection of feeding pins through the wall of 45 cylindrical member 16, as will appear more fully later.

In conventional typewriters the platen is rotated by the operator grasping a knob disposed on either end of the reciprocatory carriage. The 50 platen may also be rotated automatically by the line spacing mechanism, which has not been shown in the present application, as the line spacing mechanism per se does not constitute a part of applicant's contribution to the art.

35

40

45

50

55

In the present modification the disc 18 is fixedly attached to a tubular member 30, journaled in the end frame to the left of the carriage, as shown in Fig. 2, which includes members 32 and 34, each of which has been broken away for the sake of clearness. The tubular member 30 is fixedly attached to a gear 36, meshing with a pinion 38, driving a gear 40, fixedly attached to a suitable knob 42 and supported upon a bracket 44 fixedly carried by the end of the end frame of the carriage 12. As the operator grasps and rotates the knob 42, the gear 40 driving the pinion 38 actuates the gear 36 and with it the platen 14.

The disc 20 located and supporting the opposite end of the cylindrical disc 16 is fixedly attached to the tubular sleeve 46, having fixedly attached thereto a knob 48. This tubular sleeve 46 is mounted for rotation in the journal 50, fixedly attached to the carriage. As the operator grasps the knob 48 and rotates the same, the platen 14 is rotated.

Pin wheel feeding device

The pin wheels 60 and 62 are rotatably mounted upon a shaft 64 eccentrically disposed with respect to the center of rotation of the platen 14. The shaft 64 has one end mounted upon a bracket 66 fixedly attached to a stub shaft 68 passing through the tubular member 30 and fixedly attached to member 44. The opposite end of the shaft 64 is mounted upon a bracket 70 fixedly attached to a tubular sleeve 12, mounted for rotation within tubular member 46. As member 44 is non-rotatably mounted, and the stub shaft 68 fixedly attached thereto, together with member 66, it can be readily seen that the eccentrically disposed shaft 64 does not rotate with the platen. The feeding pins 74 in pin wheel 60 and the feeding pins 76 in pin wheel 62 cooperate with the apertures 24 and the slots 26 to drive the pin wheels 60 and 62 as the platen 14 is rotated. The feeding pins 74 and 76 function the same as gear teeth, which mesh with what might be referred to as gear sectors, that is, the edges of holes 24 and the edges of slots 26 respectively.

Lateral adjusting mechanism for pin wheels

The pin wheel 62 is adjustable laterally or axially along the shaft 64. This is permissible due to the slots 26 which extend longitudinally in equally spaced relation from the end of the platen toward the center thereof, or as far as desirable. The pin wheel 62 is provided with a hub 80 having a flange 82 at one end thereof and a flange 84 at the opposite end. The flange 84 abuts a collar or yoke 86 integral with an internally threaded member 88 threadedly engaging a threaded rod 90 terminating in a knob 92. As the knob 92 is rotated, the rod 90 which cannot be moved axially, actuates member 88 either to the left or the right, as viewed in Fig. 2. When it is actuated to the right, the collar or yoke 86 engaging the flange 84 moves the pin wheel 62 to the right. The flange 82 on the left end of the hub 80, as viewed in Fig. 2, engages an inwardly projecting annular flange 94 integral with member 96, which is rotatably mounted upon member 98 and held in position by a nut 91. When member 88 is actuated to the left as viewed in Fig. 2, the inwardly projecting flange 94 integral with member 86, engaging the flange 82, actuates the pin wheel 62 to the left.

Member 88 is connected to member 98 by a bridging member 99 that extends between the flange 84 and the outer path of movement of the feeding pins 76 carried by the pin wheel 62.

Thus, it may be seen, that as the knob 92 is rotated, the pin wheel 62 is actuated to the left or to the right, as viewed in Fig. 2. It is thereby possible to use a pin wheel feeding device with marginally punched record material of various widths. If, for example, record material eight inches wide is used, feeding wheels 60 and 62 are adjusted so as to engage the marginal holes in such paper. If the paper is an inch or two wider, the pin wheel 62 is moved approximately an inch or two to the right, so as to accommodate the wider paper. In order to utilize the paper it is necessary to fill or cover the slots between the pin wheels. If these slots are not covered, the type impinging upon the record material would mutilate the same.

Slot filling members

Slot filling members or strips 100 are provided with longitudinal tongues 102 seated in grooves 104 extending along the edges of the slots 26. Members 100 are lined or faced with a rubber facing 106. One end of each strip 100 is fixedly attached to the periphery of member 96, which is adjusted to the right or to the left as the case may be, in unison with the pin wheel 62. The grooves 104 are curved inwardly, so as to cause a portion of the strips 100 to lie within the periphery of the platen when not in use. Thus, it may readily be seen that the strips 100 passing through the grooves 104 are actuated with the pin wheel, so that as the pin wheel 62 is moved axially to the right, as viewed in Fig. 2, the space vacated by the pin wheel is filled with the strips 100. When the pin wheel is actuated to the left, the feeding pins 76 are moved into the portion of the slots vacated by the strips 100.

The strips 100, together with annular member 96, rotatably mounted upon member 98, rotate with the platen 14, so as to present a smooth writing surface to the writing portion of the platen. Thus, it is seen that one platen may be used for various widths of paper without the insertion of new sections of platen, without removal of sections of platen, or without the interchange of platen sections.

When it is found desirable to use the typewriter in writing letters, addressing envelopes and the like, where writing material is used that is not provided with marginal feed holes, the pin wheel 62 may be actuated to the right sufficiently far to provide clearance for both of the margins of the writing material between the pins of the pin wheels 60 and 62, as clearly shown in Fig. 1, wherein a piece of paper is shown in writing position between the pin wheels 60 and 62.

For the convenience of disclosure the wheels of the platen have been shown of much heavier material than would be required in actual production. This has been done for the sake of clearness.

Instead of one end being provided with slots, both ends of the platen could be slotted, the slots of one end being arranged in staggered relation with respect to the slots of the other end. The feeding pins would then also be arranged in staggered relation, which would require marginally punched record material provided with rows of apertures arranged in staggered relation. Filler members found in each of the slots of both ends may be adjusted axially so as to expand or contract the effective area of the platen. This may be accomplished by adjusting either one of the pin wheels axially, or by adjusting both axially. By this arrangement a greater differential in

width of record materials may be used upon the platen.

Although the preferred modification of the device has been described, it will be understood that within the purview of this invention various changes may be made in the form, details, proportion and arrangement of parts which generally stated consist in a device capable of carrying out the objects set forth, in the novel parts, combination of parts and mode of operation, as disclosed and defined in the appended claims.

Having thus described my invention, I claim:

1. In a pin wheel feeding typewriting machine, a pair of pin wheels, a platen including a cylindrical member having openings adjacent one end and a plurality of longitudinal slots adjacent the other end, the openings and the slots receiving the feeding pins of the pin wheels, and a plurality of filler members one for each of the slots adjustably mounted therein, said filler members cooperating with the cylindrical member so as to present a uniform writing surface over at least a portion of the slotted end of the cylindrical member.

2. In a pin wheel feeding typewriting machine, a platen including a cylindrical member enclosing the pin wheel, said cylindrical member including a plurality of longitudinal slots equally spaced around the periphery of the cylinder, and a plurality of filler members adjustably mounted in fixed relation with respect to the pin wheel so that as the pin wheel is adjusted longitudinally the filler members move with the pin wheel so as to present a uniform writing surface on one side of the pin wheel.

3. In a writing machine having feeding pins for advancing the record material in registry past writing position, a platen including a cylindrical member having slotted openings arranged in equally spaced relation around the periphery adjacent one end, the feeding pins projecting through the slots, and filler members adjustably mounted in the slots to one side of the feeding pins, said filler members cooperating with the slotted portion of the cylinder to present a uniform writing surface over at least a portion of the slotted end of the cylindrical member.

4. In a writing machine, the combination of a platen including a cylindrical member having a plurality of equally spaced longitudinal slots adjacent one end thereof, filler members adjustably mounted in the slots with adjustable feeding pins adapted to project through the slots cyclically, means for supporting the feeding pins, said feeding pins being adjustable axially with respect to the platen, the filler members being adjustable in unison with the feeding pins so as to cooperate with the slotted portion of the cylinder to present a uniform writing surface along one side of the feeding pins.

5. In a pin wheel feeding device for advancing superimposed strips of punched record material in registry past the writing position of a writing machine, the combination including a cylindrical platen having a plurality of longitudinal slots adjacent one end thereof, said platen having a resilient facing, adjustable members for filling at least portions of said slots, said adjustable members being provided with a resilient facing so as to present a uniform surface to at least a portion of the slotted end of the platen.

6. In a pin wheel feeding device for advancing superimposed strips of marginally punched record material in registry past the writing position of a writing machine, the combination of a pair

of pin wheels, one of which is adjustably mounted for axial adjustment with a cylindrical platen having a row of peripherally arranged pin holes adjacent one end for the feeding pins of one of said pin wheels, and a plurality of longitudinal slots in the other end thereof, the feeding pins of the adjustably mounted pin wheel projecting through said slots which permits axial adjustment of said pin wheel.

7. In a pin wheel feeding device for advancing superimposed strips of marginally punched record material in registry past the writing position of a writing machine, the combination of a cylindrical platen having peripherally arranged holes adjacent one end and a plurality of longitudinal slots adjacent the other end, with a pair of eccentrically disposed pin wheels one of which has feeding pins projecting through said holes and the other has the feeding pins projecting through said slots, the feeding pins cooperating with the holes and the slots as gear teeth to rotate the pin wheels at substantially the same peripheral speed as the peripheral speed of the platen.

8. In a pin wheel feeding device for advancing superimposed strips of marginally punched record material in registry past the writing position of a writing machine, the combination of a pair of pin wheels, one of which is adjustably mounted for axial adjustment with a cylindrical platen having peripherally arranged holes adjacent one end for the feeding pins of one of said pin wheels, a plurality of longitudinal slots in the other end of the platen, the feeding pins of the adjustably mounted wheel projecting through the slots, which permit axial adjustment of said pin wheel, and filler members for the portion of the slots located between the feeding wheels.

9. In a pin wheel feeding device for advancing superimposed strips of marginally punched record material in registry past the writing position of a writing machine, the combination of a pair of pin wheels, one of which is adjustably mounted for axial adjustment with a cylindrical platen having peripherally arranged holes adjacent one end for the feeding pins of one of said pin wheels, a plurality of longitudinal slots in the other end of the platen, the feeding pins of the adjustably mounted wheel projecting through the slots, which permit axial adjustment of said pin wheel, and adjustable members one for each of the slots adapted to be adjusted into position to close the portions of the slots located between the pin wheels to present a uniform writing surface.

10. In a pin wheel feeding device for advancing superimposed strips of marginally punched record material in registry past the writing position of a writing machine, the combination of a pair of pin wheels, one of which is adjustably mounted for axial adjustment with a cylindrical platen having peripherally arranged holes adjacent one end for the feeding pins of one of said pin wheels, a plurality of longitudinal slots in the other end of the platen, the feeding pins of the adjustably mounted wheel projecting through the slots, which permit axial adjustment of said pin wheel, said slots having the sides thereof grooved, and tongued filler members adjustably mounted in the slots to fill a portion thereof to one side of the pin wheel feeding device.

11. In a pin wheel feeding device for advancing superimposed strips of marginally punched record material in registry past the writing position of a writing machine, the combination of a

- pair of pin wheels, one of which is adjustably mounted for axial adjustment with a cylindrical platen having peripherally arranged openings adjacent one end for the feeding pins of one of 5 said pin wheels, a plurality of longitudinal grooved slots in the other end of the platen, the feeding pins of the adjustably mounted pin wheels projecting through said slots which permit axial adjustment of said pin wheels, and 10 means mounted for adjustment with said adjustable pin wheel for closing the portions of the slots located intermediate the pin wheels.
12. In a pin wheel feeding device for advancing superimposed strips of marginally punched record material in registry past the writing position of a writing machine, the combination of a pair of pin wheels, one of which is adjustably mounted for axial adjustment with a cylindrical platen having peripherally arranged openings 15 adjacent one end for the feeding pins of one of said pin wheels, a plurality of longitudinal grooved slots in the other end of the platen, the feeding pins of the adjustably mounted pin wheel projecting through said slots which permit axial 20 adjustment of said pin wheels, adjustable filler members having tongues seated in said grooved slots, and means adjustably mounted with the pin wheel for adjusting the filler members in unison with the adjustment of the pin wheel.
13. In a pin wheel feeding device for advancing superimposed strips of marginally punched record material in registry past the writing position of a writing machine, the combination of a cylindrical platen having peripherally arranged 25 holes adjacent one end and a plurality of longitudinal slots adjacent the other end, with a pair of eccentrically disposed pin wheels one of which is adjustably mounted for axial adjustment, means accessible from the exterior of the platen 30 for axially adjusting said adjustable pin wheel, and means for filling the portions of the slots between the pin wheels, so as to present a uniform writing surface on the platen.
14. In a pin wheel feeding device for advancing superimposed strips of marginally punched record material in registry past the writing position of a writing machine, the combination of a cylindrical platen having peripherally arranged 35 holes adjacent one end and a plurality of longitudinal slots adjacent the other end, with a pair of eccentrically disposed pin wheels one of which is mounted for axial adjustment, the feeding pins of one of the pin wheels extending through said holes and the feeding pins of the adjustable pin 40 wheel extending through said slots, means accessible from the exterior of the platen for adjusting said adjustably mounted pin wheel, and means rotatably mounted upon said adjusting means for filling the portions of the slots between the pin wheels.
15. In a pin wheel feeding device for advancing superimposed strips of marginally punched record material in registry past the writing position of a writing machine, the combination of a cylindrical platen having peripherally arranged 45 holes adjacent one end and a plurality of longitudinal slots adjacent the other end, with a pair of eccentrically disposed pin wheels one of which is mounted for axial adjustment, the feeding pins 50 of one of the pin wheels extending through said holes and the feeding pins of the adjustable pin wheel extending through said slots, means accessible from the exterior of the platen for adjusting said adjustably mounted pin wheel, and means rotatably mounted upon said adjusting means for filling the portions of the slots between the pin wheels.
16. In a pin wheel feeding device for advancing superimposed strips of punched record material in registry past the writing position of a writing machine, the combination including a pair of eccentrically mounted pin wheels, one of which is adjustable axially, a cylindrical platen 55 having peripherally arranged openings adjacent one end for the feeding pins of one of said pin wheels and a plurality of longitudinal slots in the other end thereof, a shaft eccentrically mounted within the platen for rotatably supporting said pin wheels, and means accessible from the exterior of the platen for axially adjusting said adjustable pin wheel having its pins projecting through said slots so as to accommodate various widths of record material.
17. In a pin wheel feeding device for advancing superimposed strips of punched record material in registry past the writing position of a writing machine, the combination including a cylindrical platen having peripherally arranged 60 openings adjacent one end and a plurality of longitudinal openings adjacent the other end, a shaft eccentrically mounted within the platen, a pair of rotary pin wheels mounted upon the shaft, one of which has its feeding pins projecting through the openings in one end of the platen, the other having its feeding pins projecting through said longitudinal openings, means accessible from the exterior of the platen for adjusting said other pin wheel axially, and means including movably mounted strips for filling the portion of the longitudinal openings located between the pin wheels.
18. In a pin wheel feeding device for advancing superimposed strips of punched record material in registry past the writing position of a writing machine, the combination including a cylindrical platen having peripherally arranged 65 holes adjacent one end and a plurality of longitudinal slots adjacent the other end, a shaft eccentrically mounted within the platen, means accessible from the exterior of the platen for holding the shaft in a stationary position, a pair of pin wheels rotatably mounted upon said shaft, the pins of one of which project through said holes and the pins of the other project through the slots, the feeding pins cooperating with the holes and the slots as gear teeth to rotate the pin wheels at substantially the same peripheral speed as the peripheral speed of the platen.
19. In a pin wheel feeding device for advancing superimposed strips of punched record material in registry past the writing position of a writing machine, the combination including a cylindrical platen having peripherally arranged openings, a shaft fixedly mounted but eccentrically disposed within the platen, a pair of pin wheels rotatably mounted upon said shaft, said pin wheels having the teeth thereof projecting through the openings of the platen, and means accessible from the exterior of the platen for adjusting at least one of said pin wheels axially the teeth thereof being shifted in the openings of the platen so as to accommodate record material of various widths.
20. In a pin wheel feeding device for advancing superimposed strips of punched record material in registry past the writing position of a writing machine, the combination including a rotary cylindrical platen having peripherally arranged openings adjacent one end and a plu- 75

5 rality of longitudinally arranged slots adjacent to the other end, an adjustably mounted shaft eccentrically disposed within the platen, a pair of pin wheels rotatably mounted upon said shaft, one of which has the feeding pins adapted to project through said openings and the other having the feeding pins adapted to project through said slots, adjustable means including a member straddling one of said pin wheels for adjusting 10 the same axially, said member including an annular race concentrically disposed with respect to the axis of rotation of the platen, and rotary means mounted upon said race including members for filling the portions of the slots intermediate the pin wheels.

21. In a writing machine having an adjustable writing area, a platen forming the writing area, said platen including a cylindrical member having a plurality of longitudinal slots equally spaced 20 around the periphery of the cylindrical member, and a plurality of filler members adjustably mounted in said slots, the adjustment of said filler members adjusting the effective width of the writing area.

22. In a writing machine having an adjustable writing area, a platen forming the writing area, said platen having a plurality of equally spaced

parallel slots, and filler members adjustably mounted in said slots, the adjustment of said filler members adjusting the size of the effective writing area.

23. In a writing machine having a positive feeding device for aligning the record material upon the writing area, the combination including a feeding device for aligning the record material upon the writing area, a platen forming the writing area, said platen including a plurality of 10 equally spaced parallel slots, and filler members adjustably mounted in said slots, the adjustment of said filler members changing the size of the effective writing area upon the platen.

24. In a writing machine having a pin feeding device for positively advancing the record material over an adjustable writing area, the combination including a pin feeding device adjustably mounted, a platen forming the writing area, said platen including a plurality of equally spaced 20 parallel slots through which at least some of the feeding pins project, and filler members adjustably mounted in said slots, the adjustment of said filler members changing the size of the effective writing area upon the platen. 25

HENRY G. DYBVIG.
